METAL BARREL DRUM BEADING MACHINE

Bror J. Lindgren, Buffalo, N. Y., assignor to
 Niagara Machine and Tool Works, Buffalo,
 N. Y., a corporation of New York

Application December 21, 1932, Serial No. 648,184

32 Claims. (Cl. 153—2)

This invention relates to a machine for effecting preliminary expanding of circumferential beads on the intermediate parts of sheet metal barrel drums, bodies or shells preparatory to completing the formation of these beads by a rolling operation according to the process which is shown and described in Letters Patent on Method of beading a sheet metal shell, No. 1,908,521, dated May 9, 1933, and more particularly to an apparatus for conveying or propelling the sheet metal barrel drums or bodies successively to said expanding apparatus and said rolling apparatus, and discharging the same from the machine after the formation of the beads thereon has been completed.

It is the object of this invention to provide an improved propelling means for feeding the drums successively to the expanding and rolling apparatus and discharging the drums from the latter after the beading operation has been completed, which are reliable and efficient in operation, and cause the drums to be propelled and beaded accurately and expeditiously.

In the accompanying drawings:

Figure 1 is a plan view showing the bead expanding and the conveyer or propelling mechanism embodying my invention, and also the bead rolling mechanism to which the drums are presented after the expanding of the beads thereon has been effected.

Figure 2 is a front elevation of the same, partly in section.

Figures 3 and 4 are elevations of the bead expanding mechanism and the adjacent parts of the drum conveying mechanism, viewed from the left and right hand ends of the expanding mechanism respectively.

Figure 5 is a vertical longitudinal section of the bead expanding mechanism, taken on line 5—5 Fig. 1.

Figure 6 is a horizontal section of the bead expanding mechanism, taken on line 6—6 Fig. 5.

Figure 7 is a vertical transverse section of the bead expanding mechanism, on an enlarged scale, together with the adjacent part of the drum conveyer mechanism, taken on line 7—7 Fig. 5.

Figures 8 and 9 are fragmentary vertical transverse sections taken on the correspondingly numbered lines in Fig. 5.

Figure 10 is a fragmentary longitudinal section, taken on line 10—10 Fig. 20.

Figure 11 is a fragmentary vertical transverse section, on an enlarged scale, taken on line 11—11 Fig. 5.

pressure fluid to the hydraulic motors in the different positions of the pilot valves which control the flow of the pressure fluid toward and from the master valves of the several motors while actuating different parts of the drum conveyer, lifter, slides and bead expanding mechanisms.

Figure 38 is a side elevation of the hydraulic pumping mechanism whereby the fluid pressure is maintained for operating the hydraulic motors whereby different parts of the conveyer, lifter, slides and expanding mechanisms are actuated, this elevation being taken upon viewing the apparatus along line 38-38 Fig. 1.

Figure 39 is a fragmentary vertical section, taken on line 38-39 Fig. 38.

Figure 40 is a vertical section taken lengthwise of the conveyer mechanism and transversely of the expanding mechanism along line 40-40 in Fig. 1, and showing the position which the conveyer mechanism occupies when beginning a forward stroke for advancing the drums in multiple, and presenting them to the bead expanding and rolling mechanisms.

Figure 41 is a similar view taken on line 41-41 Fig. 1, but showing the drum conveyer mechanism advanced about one-half of its forward stroke.

Figure 42 is a view similar to Fig. 41 but showing the position of the parts of the drum conveyer mechanism when the same reaches the end of a forward stroke.

Figure 43 is a fragmentary vertical section, on an enlarged scale, taken transversely of the conveyer mechanism and lengthwise of the expanding mechanism along line 43-43 Fig. 1.

Figures 44 and 45 are similar views taken on lines 44-44 and 45-45 Fig. 1, respectively.

Figures 46, 47, 48 are fragmentary vertical longitudinal sections, on an enlarged scale, of the conveyer mechanism, taken on lines 46-46, 47-47 and 48-48 Fig. 1, respectively.

Figure 49 is a fragmentary horizontal section taken on line 49-49 Fig. 48.

Figure 50 is a fragmentary side elevation of one of the abutment or stop arm depressors viewed from a plane along line 50-50 Fig. 1.

Figure 51 is a fragmentary vertical section taken on line 51-51 Fig. 48.

Figure 52 is a fragmentary horizontal section taken on line 52-52 Fig. 43.

In the following description similar characters of reference indicate like parts in the several figures of the drawings:

Each of the barrel drums, bodies or shells which is adapted to be operated upon by the mechanism forming the subject of the present application comprises a cylindrical body 100 of sheet metal upon the opposite ends of which circumferential laterally projecting flanges 101 have been previously formed, as shown in Figs. 13, 43 and 44, preparatory to being introduced into the present machine for the purpose of forming thereon two laterally projecting circumferential beads 102 between opposite ends thereof, of which beads are preferably spaced equal distances from the longitudinal center of the body, as shown in Fig. 45.

In actual practice each of these beads is formed by two successive operations, the first of which serves to expand the metal circumferentially on a part of the cylindrical body of the barrel without appreciably stretching or thinning of the metal; while the second operation serves to roll this expanded metal so that a completed bead is formed on the body which projects a substan-

tial distance laterally from the side of the body and brings the two side walls of each bead closer together and more nearly parallel to radial lines drawn from the axis of the barrel so that these beads will serve more effectively for bearing surfaces on which the barrel may be rolled while loaded with various contents, without liability of the beads breaking down or causing leakage.

These operations of preliminarily expanding a part of the body of the barrel and partially forming the beads and then rolling this expanded part of the barrel body for the purpose of completing the formation of the beads without thinning the metal but instead insuring the fullest strength of the same, forms the subject of Letters Patent of the United States No. 1,908,521 dated May 9, 1933, and to which reference may be had for a more complete disclosure of this process.

The present application is based on the mechanism whereby the preliminary expanding and partial forming of the bead on the body of the barrel is effected, and also on the conveyer mechanism whereby the unbeaded barrel bodies or drums are fed first to this expanding mechanism, then to a machine which operates to roll the partially formed beads into their completed form, and then discharges the barrel body having the completed beads thereon from the machine. The details of this rolling mechanism, however, forms no part of the present application and is only shown diagrammatically in the present case for the purpose of illustrating the operation of the conveyer mechanism relative thereto.

The numeral 103 represents generally the main part of the stationary frame of this machine which may be of any suitable construction for the purpose of supporting the various working parts of the mechanism forming the subject of this application.

In its general organization this mechanism 40 comprises an expanding mechanism A whereby parts of the cylindrical body of the barrel are expanded in the process of forming the circumferential beads thereon, a rolling mechanism B whereby the expanded parts of the barrel body 45 are rolled into shape for the purpose of completing the formation of the beads thereon, and a conveyer mechanism C whereby the barrel bodies are fed through the machine and successively presented to the expanding mechanism and 50 to the rolling mechanism, and then discharged from the machine.

This conveyer mechanism is arranged lengthwise of the machine while the expanding mechanism and the rolling mechanism are arranged transversely of the longitudinal path of the barrel drums as the latter progress through the machine, the expanding mechanism and the rolling mechanism being arranged parallel with each other, and said expanding mechanism being arranged adjacent to the front or receiving part of the conveyer mechanism and the rolling mechanism being arranged adjacent to the rear or delivery part of said conveyer mechanism.

Drum conveyer mechanism

This conveyer mechanism in the preferred form shown in the drawings is constructed as follows:

Arranged lengthwise of the machine is a longitudinal track upon the front part of which the barrel bodies are placed either manually by the operator or by mechanical means, in a position in which the axis of the body is arranged horizontally and transversely relative to this track, and over which this body is rolled while in this

position, and presented successively to the bead expanding mechanism and the bead rolling mechanism, and then discharged from the rear or delivery end of this track.

- 5 This track in the preferred organization comprises two longitudinal parallel front rails 104, two longitudinal parallel intermediate rails 105, and two longitudinal parallel rear rails 106 which are stationarily mounted on the main frame in 10 any suitable manner, the members of each pair being arranged on opposite sides of the longitudinal center of the track and spaced a suitable distance apart so as to support the sheet metal drums on their undersides adjacent to the flanges 15 101 at opposite ends thereof as the drums are rolled from the front end of the track to the rear end thereof in their progress through the machine.

The rails of the front pair terminate short of 20 the longitudinal center of the expanding mechanism which extends transversely across the path of the drums, the intermediate pair of rails extends from a point immediately in rear of the longitudinal center of the expanding mechanism 25 to a point in advance of the longitudinal center of the rolling mechanism which extends across the path of the drums, and the rear pair of rails 106 extends from a point in rear of the longitudinal center of the rolling mechanism to the rear 30 end of the track.

In the preferred construction the two rails of the front pair are arranged comparatively close together, while the two rails of each of the intermediate or rear pair are arranged further apart 35 for the purpose of adapting the track to the mechanism which operates to move the drums over the track as the drums are advanced to and from the expanding station; also from and to the rolling station; and also delivering the same from the 40 expanding station.

After a drum which is to be beaded has been placed upon the front rails 104 of the track, as shown in Fig. 41, the operator rolls this drum forwardly into a position in which the drum comes 45 within the working range of the conveyer mechanism, which last-mentioned position is represented by the drum located at the extreme left in Fig. 40. This position, for convenience of description, will be referred to as the first or receiving station No. 1. During the first step of the 50 operation of the conveyer mechanism the drum is advanced toward the rear of the machine and left temporarily at rest in a position which will be designated as the second station No. 2 preparatory to expanding the body of the barrel for producing the partially formed beads thereon.

During the second step of the operation of the conveyer mechanism the drum is advanced from the second station to a position between the expanding mechanism and the rolling mechanism, which position will be referred to hereafter as the third or intermediate station No. 3.

During the third step of the conveyer mechanism the drum is fed from the intermediate station No. 3 to a position in which the drum can be operated upon by the rolling mechanism, which last-mentioned position will be referred to as the rolling position station No. 4.

During the last or fourth step of the conveyer mechanism the drum is taken from station No. 4 and advanced to a position on the rear rails of the track, from which the beaded drum is removed by an attendant or otherwise, which last-mentioned station will be referred to as the final 70 station No. 5.

After the drum reaches the first, second, third and fourth stations the same is prevented from rolling backwardly by detent means associated with each of these stations, which detent means, however, permit the free forward movement of the drums over the track. In the preferred form the detent means associated with the rails of the tracks at each of the stations one, two, three and four are constructed as follows:

The numeral 107 represents two detent dogs or 10 pawls arranged in front of each of the stations one, two, three and four, and transversely in line with each other, and each of these detent dogs being so mounted at its lower end that when the same is in its elevated operative position the same 15 extends at an incline from the front toward the rear part of the machine and across the path of the drums, as shown in Figs. 40, 41 and 42. While in its inoperative position each of these detent dogs is deflected downwardly into a horizontal position by engagement therewith of the drum which rolls over the same, and after the drum has passed the rear end of this dog, the latter is again automatically elevated into its operative 20 position so as to engage the rear side of the drum 25 and thereby prevents the latter from rolling backwardly.

Each of these detent dogs is mounted so as to yield under the pressure of a drum during the forward movement of the latter over the respective part of the track, and is then automatically elevated after the drum passes the respective detent dogs by means which are preferably constructed as follows:

The numeral 108 represents a pin whereby the 35 lower end of each detent dog 107 is pivotally connected with a plate 115 on the adjacent rail of the track so as to permit this dog to swing vertically into and out of its operative position. The detent dog is yieldingly held in its elevated rearwardly inclined position by means which comprise a horizontally movable shifting rod 109 pivotally connected at one end with a short arm 110 projecting downwardly from the detent dog below the pivot thereof, and guided at both ends 40 in lugs 111 on the adjacent part of the plate 115, and a spring 112 surrounding the shifting rod 109 and bearing at one end against the guide lug 111, while its opposite end bears against an abutment or shoulder 113 on the shifting rod, as best shown 45 in Figs. 42, 48 and 49.

The rising movement of this detent dog under the action of the spring 112 is limited by means of a stop pin 114 arranged on the adjacent part of the plate 115 and engaged by the shifting arm 50 110 of this dog, as shown in Fig. 48. Due to this construction the drum is free to deflect each detent dog 107 downwardly from the upper operative position, shown by full lines in Fig. 40, to the horizontal inoperative position shown in Fig. 42, 55 until the drum passes this dog, after which the dog again is raised into its operative position by the spring 112 so as to engage the rear side of the drum and prevent the same from again moving backwardly on the track.

For the purpose of accurately positioning each of the detent dogs 107 and causing the same to engage the rear side of the drum properly, this dog and its spring return mechanism are made adjustable lengthwise of the track by adjustably 60 connecting the plate 115 with the adjacent part of one of the front rails 104 by means of bolts 116 secured to said rail and passing through a longitudinal slot 117 in the plate 115, as shown in 65 Figs. 42, 48 and 49.

As a drum arrives at each of the stations one, two, three and four, the same is temporarily engaged on its front or advancing side by a stop device which prevents the same from advancing for the time being until other functions of the machine have been performed, after which these stop devices are retracted automatically out of the path of the drums in order to permit them to again advance another step from one station to the next following, under the action of the conveyer mechanism.

The stop devices for this purpose at the several stations are identical in construction and are preferably constructed as follows:

15 The numeral 118 represents two stop dogs or pawls arranged adjacent to the front side of each of the drum stations No. 1, 2, 3, 4 and spaced transversely apart so that the same are capable of engaging each of the drums on its lower front part adjacent to opposite ends thereof when these stop dogs are in their operative elevated positions.

20 Each of these stop dogs is pivoted at its lower end by means of a pin 119 on a supporting plate 120 which is mounted on the adjacent guide rail of the track and is yieldingly held in its elevated position by means of a shifting rod 121 connected at one end with a short arm 122 on the stop dog adjacent to its pivot 119 and guided in a lug 123 25 on the supporting plate 120, and a return spring 124 surrounding the shifting rod 121 and bearing at one end against the guide lug 123 and at its opposite end against a shoulder consisting of a screw nut 125 arranged on the shifting rod 121.

30 35 When free, each stop dog is elevated by the spring 124 into a position in which the same inclines forwardly and upwardly from its pivot 119, so that the same stands in the path of the drum and arrests the same at one of the stations, as shown by full lines in Fig. 42 and by dotted lines in Fig. 47.

40 45 The movement of the stop dog 118 in this direction is limited by engagement with a stop pin 126 mounted on the adjacent part of the supporting plate 120. The stop dogs at each station remain in this elevated position for temporarily arresting the forward movement of each drum in order to permit certain functions of the machine to be performed, and then these stop 50 55 dogs are depressed into a position below the path of the drums, as shown by full lines in Fig. 47, thereby enabling the drums to continue their forward movement to the next station. The mechanism whereby the stop dogs are thus depressed will be presently described in connection with other parts.

60 65 In order to enable the stop dogs 118 to be adjusted lengthwise of the drum supporting track and to arrest each drum in the proper position at each station, each of the supporting plates 120 is made horizontally and lengthwise adjustable on the adjacent stationary rail of the track by means of adjusting screws 127 secured to the respective rail and passing through a horizontal longitudinal slot 128 in the supporting plate 120, as shown in Fig. 47.

70 75 In its preferred form the feed mechanism whereby the drums to be operated upon are fed in processional order over the supporting track and to and from the expanding mechanism and rolling mechanism, is constructed as follows:—

Adjacent to the area of the drum supporting tracks and reciprocating horizontally and lengthwise relatively thereto is a feeding frame or rack 75 which in its preferred construction comprises

a front section and a rear section which are connected so as to move as a unit. The front section comprises two outer longitudinal bars 129, 129a arranged lengthwise along the outer sides of the front and intermediate rails 104, 105, two inner longitudinal bars 130 arranged lengthwise along the inner sides of said front and intermediate rails 104, 105, a front cross bar 131 connecting the front ends of the longitudinal bars 129, 129a, 130, and a rear cross bar 132 connecting the rear ends of said longitudinal bars 129, 129a, 130. The rear section of this feeding frame comprises two longitudinal outer bars 132, 132a which are arranged along the outer sides of the intermediate and rear rails 105, 106, two inner longitudinal bars 133 arranged along the inner side of the intermediate and rear rails 105, 106, a front cross bar 134 connecting the front ends of the longitudinal bars 132, 132a, 133 and a rear transverse bar 135 connecting the rear ends of said longitudinal bars 132, 132a, 133.

10 15 20 25 30 35 40 45 50 55 60 65 70 75 80 85 90 95 100 The rear cross bar 131 of the front feeding frame section and the front cross bar 134 of the rear feeding frame section are connected with each other by means of coupling clips 136, as best shown in Figs. 1, 45, 51. This feeding frame may be guided in its longitudinally reciprocating movement in any suitable manner but the means which are preferably employed for this purpose consist of a plurality of guiding rollers 137, 137a mounted on brackets 138, 138a mounted on the main frame of the machine and engaged on their upper sides by the undersides of the longitudinal outer bars of the feeding frame, so as to form a rolling support for the latter, as shown in Figs. 1, 41, 42, 44, 45 and 51.

Upon this feeding frame are mounted a plurality of feeding dogs or pawls 140 which are adapted to engage with the lower front part of the drums for the purpose of shifting the same intermittently from the first station No. 1, successively to the second, third, fourth and fifth stations of the machine, and into a delivery position on the rear part of the track preparatory to being removed manually or otherwise from the machine. These feeding dogs are preferably mounted in successive pairs on the feeding frame, each pair being adapted to engage with the rear side of a drum for the purpose of moving the latter from one station to another by engaging the drum adjacent to opposite ends thereof during a forward stroke of the feeding frame, but during a rearward stroke of this frame, these feeding dogs are deflected downwardly and out of the path of the respective drums by engagement with the undersides of the latter.

For this purpose each of these feeding dogs or pawls is yieldingly mounted on one of the longitudinal bars of the feeding frame in the following manner:

The numeral 141 represents a pivot pin which pivotally connects the lower end of each feeding dog with the adjacent longitudinal bar of the feeding frame, as shown for example in Fig. 46. 65 70 75 80 85 90 95 100 This feeding dog is yieldingly held in its elevated operative position in which it inclines rearwardly and upwardly from its pivot 141 by means of a shifting rod 142 connected at one end with a short arm 143 projecting downwardly from the respective feeding dog below the pivot thereof, a guide lug 144 which is arranged on said bar and receives said shifting rod 142, and a return spring 145 surrounding the shifting rod, and bearing at one end against the guide lug 144, 75

- while its opposite end bears against a shoulder reference to their respective stations at this time. 146 on the shifting rod, which shoulder preferably has the form of a screw nut whereby the tension of the spring 145 may be varied. The 5 upward movement of the feed pawl 140 is limited by a stop pin 141 arranged on the adjacent longitudinal bar of the feeding frame and adapted to be engaged by the operating arm 143 of the respective feeding dog.
- 10 During the backward movement of the feeding frame each of the feeding dogs is deflected downwardly into a substantially horizontal and inoperative position by engagement with the underside of the next rearward drum on the track, 15 which position of the dogs is indicated by dotted lines in Fig. 46. As soon as the feeding dog has passed back far enough to clear the respective drum then the spring 145 operates to raise said feeding pawl into its rearwardly inclined position 20 in which it operatively engages with the front side of the drum, as shown by full lines in Fig. 46, preparatory to compelling the same to move forwardly with the feeding frame during the next forward stroke of the same.
- 25 While the feeding frame is effecting its backward stroke, means are provided for temporarily depressing the stop dogs 118 below the path of the drums so that the latter during the subsequent forward stroke of the feeding frame will be 30 free to move from the front to the rear part of the track while being advanced from one station to another.
- The preferred means for this purpose comprise a plurality of depressing plates 148 arranged on 35 the feeding frame in such position that during each backward stroke of the feeding frame one of said depressing plates will engage with the free end of one of the stop dogs 118 and depress the same from its elevated operative position, as 40 shown by dotted lines in Fig. 47, to its lower inoperative position below the path of the drums over the rails, as shown by full lines in Fig. 47.
- During the following forward stroke of the feeding frame from the front to the rear end of the 45 machine, each of these depressing plates or members 148 holds the respective stop dog 118 in its lower inoperative position a sufficient length of time to permit the next following drum to move over the same, and as the feeding frame completes its forward stroke the depressing plate 148 50 associated with each stop dog 118 again moves forwardly out of the path of the respective dog 118 so that the latter can be raised by its spring 124 and assume a position in which it will obstruct the path of the next following drum, and be engaged by said drum at the end of the forward stroke of the feeding frame.
- It follows from this that at the end of each 55 forward stroke of the feeding frame each of the drums arranged at stations one, two, three and four will be engaged on its front side by a pair of stop dogs, and on its rear side by a pair of feeding dogs, and also by a pair of detent dogs, as shown in Fig. 42, thereby holding the respective drums in their centered position relative to the respective stations.
- During the initial part of the next following return or backward stroke of the feeding frame toward the front end of the machine, the pair of 60 feeding pawls associated with each drum will be moved backwardly and leave each drum within the grip of two stop dogs engaging with the front side thereof, and two detent pawls engaging with the rear side thereof so that the drums continue 65 to be held in their proper centered position with
- During the last part of the return or backward movement of the feeding frame each pair of feeding pawls is deflected downwardly by the next following drum preparatory to engaging the rear side thereof, and each pair of stop dogs is depressed by the respective depressing plates 148 so as to clear the path of each drum in front of the same and permit it to be subsequently moved forwardly toward one station or the other by 10 the next following forward or operative stroke of the feeding frame.
- In order to enable the depressing plates 148 to be accurately adjusted on the feeding frame so as to depress the respective stop dog at the proper time, means are provided for adjusting each depressing plate on the feeding frame. These means, as shown in Figs. 45, 49 and 50 preferably comprise an adjusting plate 149 carrying the depressing plate 148, and adjusting screws 150 secured to one of the longitudinal feed bars and passing through a longitudinal slot 151 in the respective adjusting plate 149.
- During the backward or return movement of the feeding frame the drums at stations 2 and 4 25 are elevated out of engagement with the feeding frame while the operations of expanding and rolling beads on the drums are being performed thereon, and the backward movement of the feeding frame therefore has no effect upon the drums 30 while located at these stations.
- In order to prevent the drums from being engaged by the longitudinal bars of the feeding frame during the backward movement of the latter while the drums are occupying stations 1, 3 35 and 5 the rails of the track adjacent to these stations are provided with elevated portions 152, 153, 154, as shown for example in Figs. 40 and 42, whereby these drums after being deposited upon these elevated portions by the feed mechanism 40 will be raised above the plane of the longitudinal bars forming part of the feeding frame so that the latter, during its return movement, will not engage said drums and thereby avoid any 45 tendency to move the same backwardly or distract their position while occupying stations 1, 3 and 5, but instead will permit them to remain undisturbed in these positions preparatory to being advanced further steps during the continued 50 operation of the machine.
- Various means may be employed for effecting the reciprocating movement of the drum or body feeding frame but it is preferable to employ hydraulically operated means for this purpose which are constructed as follows:— 55
- The numerals 155, 155a represent longitudinal gear racks secured to the outer sides of the outer longitudinal bars 129 of the front feed frame section. The teeth on the underside of these gear racks are engaged by two gear wheels 156, 60 156a which are mounted on a transverse horizontal feed shaft 157 journaled in suitable bearings on the adjacent part of the main frame, as best shown in Fig. 43. The numeral 158 represents the cylinder of a hydraulic motor which 65 is mounted on the lower part of the main frame and contains a piston 159 which is reciprocated therein by admitting and exhausting a pressure fluid to and from opposite ends of the cylinder 158. The piston 159 is provided with a piston 70 rod 161 and the latter is connected with a horizontally reciprocating gear rack 162 which meshes with a gear pinion 163, as shown in Figs. 43 and 52. The numeral 164 represents an upright intermediate shaft journaled on the main 75

frame and on the lower end of this shaft gear wheel 163 is secured while its upper end is operatively connected by means of a pair of co-operating miter gear wheels 165, 166 with the 5 feed shaft 157, as shown in Fig. 43.

It follows from this construction that when the live pressure medium is admitted into the cylinder 158 at one end thereof and the spent pressure medium is exhausted from the opposite 10 end of the same the piston 159 therein will be moved in one direction and cause the gear wheels 156 through the medium of the mechanism associated therewith, to move the feeding frame lengthwise of the machine in one direction; and upon reversing the connection for the live and 15 spent pressure medium at the opposite end of the cylinder 158 this mechanism will operate to move the feeding frame in the reverse direction. By these means a continuous longitudinal reciprocating movement is imparted to the feeding frame and the drums are successively moved 20 from one station to another while the machine is in operation.

To permit the lateral adjustment of the several parts of the feeding mechanism to suit drums of different lengths the following mechanism is employed:

Attached to the bars 130 and 133 are upright brackets 800, 801, the lower ends of which are 30 split and have clamping bolts 802, 803 for adjustably securing these brackets to the cross bars 131, 134, 135, 138. By loosening these bolts the bars 130, 133 carrying the feeding dogs 140 can be laterally adjusted according to the size of 35 drum to be fed.

The rails 104, 105, 106 can also be adjusted laterally by loosening the clamps 804 at the inner ends of the rail frame 104 and the clamps 805 at the both ends of the central rail frame 105, 40 and clamp 806 at the inner ends of the delivery rail frames 106, as shown in Figs. 1 and 40, thereby permitting these rails to be shifted laterally on the main frame and then held in place.

The guiding rollers 137 in brackets 138 carrying the longitudinal outer bars 129 and 132 remain fixed but the rollers 137a in brackets 138a 45 are laterally adjusted through the medium of gear racks 807 and pinions 808 mounted on shafts 809, as best shown in Figs. 2 and 43. Pinned to the outer ends of the shafts 809 are 50 hand wheels 810.

When the rail 129a carrying the gear rack 155a is adjusted laterally it is essential that the gear 55 156a be moved with it. To do this the set screw 811 on the gear 156a must be loosened.

The shaft 157 is feathered at 812 and gear 156a is slidably keyed to this shaft.

The numeral 813 represents a clamp and 814 clamp bolts to hold the gear rack 807 in a fixed 60 position after adjustments have been made.

The longitudinal bar 129a carrying the right hand feed gear rack 155a is adjustably connected with the right hand end of the adjacent cross bar 131 of the feeding frame by means 65 which include a bracket 814a projecting downwardly from said bar 129a and embracing the bar 131, and a clamping bolt 814b connecting the ends of the split part of said bracket surrounding the cross bar 131, as shown in Fig. 43.

By thus adapting the rails and bars of the track and conveyer to the length of drum which is being beaded it is possible to engage the feeding, detent and stop dogs with the drum, as will best suit the formation of the beads thereon and 75 not interfere with the beading operation.

Drum lifting and holding mechanism

After each drum arrives at the bead expanding mechanism, which is represented by station No. 2, the drum conveyer mechanism reaches the end of its forward stroke and the drum remains at rest during the following backward stroke of the conveyer mechanism, and during this period of rest, so far as the forward longitudinal movement of the drum is concerned, the same is lifted into a position in which its opposite ends are in alignment with the two sections of the expanding mechanism which are arranged on opposite sides of the path of the drums and adapted to form partial beads circumferentially on the drum adjacent to opposite ends thereof. 10

This lifting mechanism cooperates with other parts so as to hold the barrel positively in its centered position with reference to the bead expanding mechanism, and as best shown in Figs. 1, 2, 5, 7, 12, 13 to 17, is constructed as follows:

The numeral 168 represents two longitudinal bars of a saddle which is adapted to raise the drum and each of which is provided on its upper side with a V-shaped seat 168a for engagement with the underside of the drum adjacent to one end thereof, so that when the seats of these two bars engage with the drum the latter will be centered with reference to this elevating mechanism and maintained in this position while being lifted. 25 These saddle bars, during the forward stroke of the conveyer mechanism, are arranged below the path of the drums, as represented by dotted lines in Fig. 7 and by full lines in Fig. 13; and after the conveyer mechanism reaches the forward end of its stroke these saddle bars rise, and by engagement with the underside of the drum, lift the latter so that the same is axially in line with the elements of the bead expanding mechanism which is adapted to form the beads on the drum, as 30 shown by full lines in Figs. 5 and 7. 35

These saddle bars form part of a vertically movable lifting frame which comprises upright bars 169 connected at their upper ends with opposite ends of the saddle bars 168, horizontal transverse bars 170 connecting the lower ends of the corresponding upright bars 169, and a vertically movable slide 171 provided with laterally projecting arms 172 which are connected with the intermediate parts of said transverse bars 170. The slide 171 is guided in its vertical movements on a guide rod 173 depending from the adjacent part of the main frame 103. The cooperating surfaces of this slide and the guide rod 173 are of non-circular form so that the slide is free to rise and fall on this rod but incapable of turning thereon, thereby always maintaining the saddle bars in the proper position relative to the parts with which the same cooperate during the operation of the machine. 50

The power for raising and lowering this lifting frame is preferably derived from a hydraulic motor having a horizontal cylinder 174 mounted horizontally and transversely on the lower part of the main frame, a piston 175 reciprocating in 65 this cylinder and provided with a piston rod 176 extending through one head of the cylinder. This piston is reciprocated by alternately admitting a live pressure fluid into and exhausting the spent pressure fluid from opposite ends of this cylinder 70 by means of a valve mechanism which will be described later on.

Motion is transmitted from this motor to the lifting frame by means of a driven lever of elbow or bell crank form and having a lower horizontal 75

arm 177 which is connected at its free end by means of a link 178 with the slide 171 and has an upwardly projecting adjusting arm 179; and a driving lever of straight form having a lower arm 180 which is connected by means of a link 181 with the piston rod 176 while its upper adjusting arm 182 is connected with the adjusting arm 179 of the driven lever. The driving and driven levers of this transmitting mechanism are so mounted and connected with each other that the vertical strokes of the lifting frame may be regulated to insure accurate alignment of the drum with the expanding mechanism in the elevated position of the drum and also to permit of adapting the machine to drums of various diameters and still maintain a uniform stroke of the piston 175 of the hydraulic motor. This is preferably accomplished as follows:

The numeral 183 represents the pivot of the driven elbow lever which is mounted horizontally and lengthwise of the machine on a bracket 184 on the lower part of the main frame; and 185 represents a rock shaft forming the pivot of the driving lever and journaled horizontally and lengthwise in a bearing 186 on a higher part of the main frame so that the axis of the driving rock lever 180, 182 is out of line with and higher than the axis of the driven rock lever 177, 179, as shown in Fig. 14. The adjustable connection between the upper adjusting arms of these levers is preferably effected by means of an adjusting block 187 preferably of square form sliding in a radial groove 188 in the arm 182, an adjusting pin 189 projecting from this block 187 into a radial slot 190 in the adjusting arm 179, and an adjusting screw 191 turning in a lug 192 on the arm 179 but held against lengthwise movement thereon and having threading engagement with a lug 193 on an adjusting plate 194 which connects with the adjusting pin 189.

By this means motion is transmitted from the driving lever to the driven lever for actuating the barrel lifting frame by power derived from the hydraulic motor 174. By turning the adjusting screw 191 in one direction or the other the point of connection between the driving and driven levers of this mechanism may be moved toward or from the axes of these levers and thereby either shorten or lengthen the stroke of the drum lifting frame relative to the throw of the piston 175 of the motor which actuates the same. This relative action of these levers is indicated diagrammatically in Fig. 17, from which it will be observed that a comparatively long arc movement of the adjusting arm 182 of the driving lever will effect a comparatively short arc movement of the driven rock lever, owing to the offset arrangement of the axes about which these levers turn, and that a shifting of the connection between the adjusting arms of these levers will produce a corresponding decrease or increase in the arc movement of the driven lever, while the arc movement of the driving lever remains the same. By this means the lifting mechanism of this machine can be readily adjusted accurately to properly elevate drums of different diameters to the mechanism which operates on the drums preparatory to forming beads thereon.

In order to enable the operator to readily determine the effective stroke of the drum lifting frame the adjusting plate 194 is provided with a longitudinal row of graduations 195 which are adapted to register with some convenient mark or location on the adjusting arm 179, for example

the upper edge of the same, as best shown in Fig. 13.

The mechanism of this machine is so timed that after the conveyer reaches the end of a forward stroke and the respective feeding dogs of the same bring a drum to the expanding station of the machine, then the lifting mechanism is operated by its motor so that the saddle engages with the underside of the respective drum and raises the same from the conveyer into a position in which the drum is axially in alignment with the operating elements of the bead expanding mechanism and enable the latter to operate properly upon the drum for the production of beads thereon.

In order to positively hold the drum in a position in which it is aligned with the expanding mechanism, means are provided which are engaged by the upper side of the drum in its elevated position so that the drum is gripped both on its underside and on its upper side and thereby reliably held in place while the bead expanding mechanism is operating upon the same.

Various means may be provided for this purpose but those shown in the drawings have been found satisfactory in practice. As there shown, these means comprise two retaining or abutment heads or bars 196 arranged above the path of the drums at the expanding station and adapted to be engaged by the upper side of the drum adjacent to opposite ends thereof when the same is in its elevated position, as shown in Figs. 5 and 7, a vertical adjusting rod 197 projecting upwardly from each of these retaining heads and slidably mounted in a pair of guide lugs 198 which are mounted on the upper part of an overhanging arch 199 forming part of the stationary frame of the machine, an adjusting collar 200 arranged upon the adjusting rod 197 between the guide lugs 198, and a set screw 201 threaded into this collar and engaging this rod. Upon loosening the screw 201 the rod 197 may be adjusted vertically in order to bring the abutment head 196 into the proper position to be engaged by the upper side of the drum when the latter has been elevated by the lifting mechanism into a position in which it is accurately in alignment with the bead expanding mechanism, thereby holding the drum reliably in place during the subsequent operations of forming beads thereon.

Bead expander slides or carriages

After the drum has been elevated from the conveyer mechanism into a position in which it is in axial alignment with the bead expanding mechanism, the same is operated upon by the expanding mechanism for producing the circumferential beads thereon adjacent to opposite ends of the drum. This expanding mechanism comprises two sections D, E which are arranged along opposite sides of the conveyer mechanism at the expanding station, and each of these expanding mechanisms is adapted to produce one of the beads on the drum at a point between the center and the end thereof, as will presently appear.

The two sections of this expanding mechanism are mounted respectively on horizontally and transversely movable slides or carriages 202d, 202e which are arranged on opposite sides of the path of the drum conveying mechanism, and each of which is guided on the main frame by means of flanges 203 arranged on the lower part of the respective slide, and moving in horizontal transverse guideways 204 formed on the adja-

cent part of the main frame 103, as best shown in Figs. 2, 5, 9 and 11.

Each of these slides or carriages is preferably actuated by a motor so that the same is retracted and the working parts thereof are out of the path of the drums while the latter are being moved forward by the conveyer mechanism, but after a drum has been moved forward to the expanding station by the conveyer mechanism and raised by the elevating mechanism into alignment with the expanding mechanism then the slides carrying the sections of the expanding mechanism are moved toward each other for the purpose of bringing the expanding elements mounted on the slides into the proper position within the respective ends of the drum, preparatory to producing the beads thereon.

The motors for this purpose preferably are of the hydraulic type and comprise power cylinders 208d, 208e mounted horizontally and transversely on the main frame below the slides 202d, 202e and are provided with pistons 208d, 208e which have rods 207 projecting through the outer head of the respective cylinder. The pistons of these motors have uniform throw and are reciprocated within their cylinders by alternately admitting live pressure medium to and discharging the spent pressure medium at opposite ends of this cylinder by valve mechanisms, as will presently appear.

In order to permit of adjusting the position of each slide 202d, and 202e with reference to the hydraulic motor which actuates the same and enable the expanding elements of the respective slide to be so located that the beads are produced at the desired place on the barrel bodies, means are provided whereby each slide may be adjusted lengthwise with reference to its motor.

In the preferred form these means, as shown in Figs. 2, 5 and 11 comprise a cross head 208 secured to the outer end of the piston rods 207, and longitudinal adjusting screws 209 which are mounted on brackets 210 on an adjacent part of the respective slides so as to be capable of rotation thereon but held against lengthwise movement thereon, and having threaded engagement with nuts 211 on the adjacent part of the cross heads 208. Upon turning the screw 209 in one direction or the other the slides and the expanding mechanism mounted thereon will be moved lengthwise of its motor but transversely of the path of the drums and thereby enable the expanding mechanism to be accurately located for performing the bead expanding operation properly on the respective end of the drum.

Means are provided for causing the two slides which carry the two sections of the bead expanding mechanism to move simultaneously, horizontally and transversely relative to the conveyer mechanism into and out of their operative position, and thus securing uniformity of action in the machine and enabling these sections to properly form the beads at opposite ends of the barrel body. A satisfactory means for accomplishing this purpose is shown in the drawings and comprise an equalizing gear wheel 212 rotatably mounted by means of a vertical axis 213 which is journaled on a part of the main frame of the machine below the path of the conveyer adjacent to the bead expanding mechanism, as best shown in Figs. 6 and 7, and meshing on its diametrically opposite sides with gear racks 214, each of which is arranged transversely of the machine and is connected at its outer end by

means of an attaching arm 215 with the respective cross head 208. By this means the pistons 208 of both hydraulic motors which shift the expander supporting carriages or slides are compelled to move in unison into and out of their operative positions and thus insures the proper timing of the operation of the two sections of this expanding mechanism on opposite ends of the drum.

Bead expanding mechanism

Upon each of the slides or carriages 202d, 202e of the bead expanding mechanism is mounted means for producing a circumferential bead adjacent to one end of the body of the sheet metal barrel by expansion of the metal thereof from the interior of the body, which means are identical in construction so that the following description of one will apply to both of these means, but for convenience in subsequently describing the operation of the machine as a whole the means for expanding a bead on one end of the barrel body is identified by the reference character D, and the means for expanding a bead adjacent to the opposite end of the barrel body will be identified generally by the reference character E.

Upon the upper part of each slide 202d, 202e is mounted a support 216 which is generally of hollow form and in effect forms a part of the respective slide and reciprocates transversely therewith. Arranged horizontally and transversely with reference to the line of movement of the barrel feeding mechanism and centrally within the hollow support 216 of each of the carriages 202d, 202e is a reciprocating shifting or follower rod 217 which is guided at its front and rear ends on guideways 218, 219 forming part of this slide or carriage. Reciprocating movement is imparted to this shifting rod by means of a motor which is preferably of the hydraulic type and mounted on the respective carriage so as to move bodily therewith.

As best shown in Figs. 1, 2, 5 and 29-37 these hydraulic motors comprise power cylinders 220d, 220e mounted respectively on the outer or rear ends of the carriages 202d, 202e and pistons 221d, 221e reciprocating lengthwise in these cylinders and each provided with a piston rod 222 which is connected by means of a coupling with the outer end of the respective shifting rod 217, as best shown in Figs. 5, 10 and 20. This coupling consists of two coupling blocks 223 which are clamped against opposite sides of the opposing ends of each piston rod 222 and the shifting rod 217 and held together by means of screws 224, one end of these blocks having threaded engagement with the piston rod, as shown at 225, and the opposite end of these blocks being provided with internal flanges 226 which engage with an annular groove 227 in the adjacent outer or rear end of the respective shifting rod 217, as shown in Fig. 10. A pressure medium is alternately admitted into and discharged when spent from opposite ends of each of the cylinders 220d, 220e for the purpose of reciprocating the pistons therein by a controlling valve mechanism which will be presently described.

The numeral 228 represents an inner or front follower which is connected with the inner or front end of each follower or shifting rod 217 and the numeral 229 is an outer or rear follower secured to the rear part of this follower rod. Around the inner or front follower 228 a plurality of expanding shoes or dies 230 are arranged

in an annular row, each of these shoes or dies being provided with a die face 231 which is of segmental form circumferentially of the axis of the follower rod and of rounded form in cross section. These several expanding shoes or dies are movable radially simultaneously for the purpose of contracting the several expanding shoes as a whole and reducing the diameter of the forming surfaces thereof in order to permit of introducing these expanding shoes into one end of the body of the sheet metal barrel which is to be operated upon and thereafter spreading or moving these shoes radially outward for the purpose of increasing the diameter of the forming surface of the several expanding shoes and causing them to simultaneously engage the interior of the sheet metal body of the barrel and deflect that part of the metal thereof which is engaged by these die faces outwardly so as to form an annular bead on the barrel body, as shown in the left hand part of Fig. 5 in connection with the section D of the expanding mechanism.

After the metal of the barrel body or drum has been thus expanded to form this annular outwardly projecting bead thereon the several die shoes are again contracted so as to reduce the diameter of the forming or die faces thereon and permit these expanding shoes to be withdrawn from the respective end of the barrel body. This radial movement of the expanding shoes is produced by motion derived from the longitudinally movable follower rod 217 and its front and rear follower heads 228, 229. The means for this purpose include a plurality of longitudinal expanding levers 232 arranged in an annular row around the follower rod 217, each of these levers being pivoted between its front and rear ends by means of a pivot 233 to the adjacent part of the carriage support 216. Each lever has one of the expanding shoes or dies 230 secured to its front end. An annular row of radial toggles or links 234 is provided each of which is pivotally connected at its inner and outer ends with the periphery of the front follower and the inner end of one of the shoes 230. An annular row of rear or front toggles or toggle links 235 is provided, each of which is pivotally connected at its inner end with the rear arm of one of the expanding levers 232 and pivotally connected at its outer end with the peripheral part of the rear follower 229, as shown in Figs 5, 8 and 9.

While each carriage or slide is effecting its forward movement the respective follower rod 217 and the followers mounted thereon are arranged in their rearmost position relative to this carriage so that the front and rear sets of toggles assume an inclined position and cause the several expanding levers and the expanding shoes or dies to be moved in a direction which will contract the shoes and permit the same to be introduced into an end of the drum or body of the barrel, as shown in connection with the right hand section E of the bead expanding mechanism.

After the expanding shoes or dies have reached the desired position within the sheet metal drum or body of the barrel, each expander supporting carriage remains at rest and the follower rod 217 and its followers 228, 229 are moved forwardly or inwardly whereby the front and rear sets of toggles 234, 235 are shifted from the inclined position shown in connection with section E to the straightened or radial position

shown in connection with section D of the expanding mechanism, thereby causing the several expanding shoes or dies to engage the bore of the sheet metal drum or body and force the same radially outward, thereby producing an annular or circumferential bead 102 on the exterior of this drum or body, as shown in connection with section D of the expanding mechanism in Fig. 5. Each expander carriage or slide remains at rest until the several expanding shoes or dies associated therewith have been contracted into their inoperative position and then the respective expander carriage or slide is again moved rearwardly or outwardly relative to the drum conveying mechanism in order to release the respective drum and permit the same to be advanced another step in its progress through the machine.

In order to guide the front part of the expanding mechanism of each section properly into the respective end of the drum or barrel body guiding means are provided which are movable with the carriage of each expanding section and engage with the inner side of the top of each drum or body. In its preferred construction the guiding means associated with each section of the expanding mechanism comprises a guide bar 236 arranged lengthwise adjacent to the upper part of the support 216 of each of the carriages or slides 202d, 202c and having its front end secured to a tubular extension 237 of the respective support 216 and provided with an inclined outer face 238, and an adjusting screw 239 arranged on the rear part of the guide bar 236 and engaging with the adjacent part of the support 216, as shown in Fig. 5. As each of the carriages 202d, 202c moves forwardly the respective inclined face 238 of the guide bar 236 engages with the upper part of the bore of the barrel body or drum at one end thereof, and raises the same into engagement with the adjacent abutment 196 until the drum engages with the horizontal rear part 241 of this bar, thereby properly centering the drum with reference to the several expanding shoes or dies before the latter are engaged with the bore of the drum and produce an outwardly projecting bead thereon. The front arms of the expanding levers 232 are preferably guided in their radial movements by radial guide slots 240 which are formed on the front ends of the support extension 237 and receive the respective arms of these levers, as best shown in Figs. 1, 2 and 5.

As an additional means for accurately locating the barrel drum or body with its longitudinal axis transversely of the conveyer mechanism and parallel with the line of movement of the carriages or slides of the two sections of the expanding mechanism, each of these slides is provided with end gaging means which are adapted to engage with opposite ends of the barrel drum or body during the last part of the forward or inward movement of these slides toward each other, and thereby definitely locate this drum between these slides preparatory to forming the beads thereon.

In the preferred construction these end gaging means comprise two gaging plates 254 arranged adjacent to the upper part of each expander supporting slide or carriage on opposite sides of the longitudinal center thereof in position to engage with the upper part of one end of the barrel drum when the respective slide is in its foremost or innermost position. Each of these end gage plates is capable of longitudinal adjustment on the respective slide for the purpose of adapting the

- same to drums of different length, this being accomplished in the present instance by means of a horizontal longitudinal adjusting rod 255 secured at its front end to the respective end gage plate 254 and passing with its rear part through a supporting lug 256 on the adjacent part of the slide, and clamping screw nuts 257 arranged on said gage supporting rod and bearing against opposite sides of said lug, as shown in Figs. 1, 2 and 7.
- 10 Each of the gage plates is also capable of radial adjustment with reference to the axis of the respective expanding mechanism by extending the rod 255 at its front end through a longitudinal slot 258 in said gage plate and providing this rod with two clamping screw nuts 259 which bear against opposite sides of said gage plate, as best shown in Figs. 1, 2 and 7.

In the operation of this machine both sections of the expanding mechanism mounted respectively on the slides or carriages are moved inwardly simultaneously and also outwardly simultaneously, but the expanding shoes of the two sections are actuated so that they perform their expanding operations successively instead of simultaneously. During these expanding operations the expanding shoes of one expanding section are first spread for forming a bead on one end of the body or drum, and then these shoes are contracted out of engagement from the drum.

30 After one set of expanding shoes has thus performed its beading operation and released the drum the other set of expanding shoes of the other section are moved radially outward for forming a bead on the opposite end of the drum or body, and then these last-mentioned shoes are again contracted out of their operative engagement from the same. By this means those parts of the metal drum adjacent to the place where each bead is being formed are free to flow in order to form the laterally projecting bead thereon without producing any undue stretching or thinning of the metal and thus avoiding weakening of the same.

In order to guide the drum or body of a sheet metal barrel into the position for locating its opposite ends relative to the respective expanding devices where the drum comes to rest under the action of the conveyer or feeding mechanism, guiding means are provided which preferably consist of two guide plates 242 secured to a suitable stationary part of the machine, and provided at their rear ends with inclined front faces 243 which converge forwardly, and straight rear parts 244 which are parallel with each other. As the drum or body of the barrel is moved forwardly by the conveyer mechanism the opposite ends of the barrel are engaged by the inclined rear parts 243 of the guides 242 and directed into the space between the parallel rear parts 244 thereof so that the drum upon reaching the expanding position is equidistant at its opposite ends from the two sections of the expanding mechanism, and the beads will be formed on the drum at like distances from its opposite ends. Each of the guides 242 is adjustably mounted on an adjacent stationary part of the machine so as to be capable of lateral adjustment to adapt the same to drums of different lengths. A suitable means for this purpose consists of a supporting arm 245 which carries one of the guide bars 242, a clamping plate 246 between which and an adjacent part 247 of the main frame said adjusting arm 245 is received, and clamping screws 248 which connect the clamping plate 246 with said frame member 247 and serve to grip said arm 245 for holding it against dis-

placement after the same, together with the guide bar 242, have been adjusted to the desired position.

After both sections of the expanding mechanism have been withdrawn from opposite ends of the drum or body of the barrel the lifting mechanism is lowered for again depositing the drum upon the adjacent part of the feeding or conveying mechanism, and then the latter advances another step to the intermediate or idle station No. 3 of the machine where the same is elevated a short distance out of engagement from the feeding mechanism by the raised portions 153 on the track so that during the subsequent return stroke of the feeding mechanism there will be no engagement of the latter with the underside of the barrel, and therefore no possibility of moving the drum back by any action of the feeding mechanism.

During the next following forward stroke of the feeding mechanism the respective feeding dogs of the conveyer mechanism engage the rear side of the drum which is located at the intermediate station No. 3 and moves the same forwardly one step to the rolling mechanism located at station 25 No. 4, and while the drum or body is located at this last-mentioned station this rolling mechanism operates to complete the formation of the annular or circumferential bead which has been 30 heretofore described.

In order to guide the drums properly between the two sections 249, 250 of the bead rolling mechanism which are arranged on opposite sides of the path of the drum or body of the barrel and operate individually upon the two partially formed beads adjacent to opposite ends of this drum, guide means are provided which preferably consist of two guide plates or bars 251 arranged adjacent to opposite sides of the path of the drum, 40 and each provided with an inclined front part 252, and a straight rear part 253. As the drum moves forwardly one or the other of its ends engages with one or another of the inclined parts 252 of the guide bars 251 and cause the drum to 45 be shifted lengthwise into a position between the parallel rear parts 253 of these bars so that it is in proper position for presentation to the bead rolling mechanism. These last-mentioned guide bars are adjustably mounted on an adjacent part of 50 the main frame by any suitable means, e. g. the means which are shown in connection with the guide bars 242 in order to adapt the guide bars 251 to drums or bodies of different lengths.

After the formation of the beads has been completed on the drums by the rolling mechanism located at station No. 4 the drum is again advanced by the feeding or conveying mechanism during the next following stroke of the same to the discharge position on the track of the machine, indicated as station No. 5, from which it is removed in any suitable manner preparatory to being assembled with heads at its opposite ends and otherwise finished as required.

The hydraulic motors which are mounted on the expander supporting slides or carriages must be supplied with fluid under high pressure in order to operate the same, and as this fluid is taken from a pressure means which is located at a definite or fixed place, and the cylinders which operate the bead expanding dies or shoes move with the carriages supporting the expanding mechanism, it is necessary to employ flexible means whereby the hydraulic pressure fluid is conducted to and discharged from each end of the cylinders

228d, 228c which form parts of the hydraulic motors, whereby the expanding dies or shoes are actuated.

It has been found that flexible hose is not satisfactory for this purpose inasmuch as it lacks strength and durability. A telescopic piping connection of metal has therefore been provided for each of the conduits leading to each end of these hydraulic motor cylinders, each of these telescopic piping connections being constructed as follows, and best shown in Figs. 1, 2, 3, 4, 5, 26, 27, 28 and 29:—

The numeral 260 represents an inner telescopic pipe of metal which is mounted stationarily on the main frame below the path of one of the expander supporting slides and provided intermediate of its ends with a lateral port or opening 261; and the numeral 262 represents an outer telescopic pipe which surrounds the inner pipe 260 and is of larger diameter and spaced therefrom by an intervening passage which communicates with the lateral opening or port 261 of the inner pipe. This outer pipe is mounted on the underside of the respective carriage or slide so as to move therewith and cause the outer pipe to be reciprocated lengthwise of the inner pipe, a tight joint being effected between opposite ends of the outer telescopic pipe 260 by means of stuffing boxes or packings 263 in order to avoid leakage at these places.

The location of the lateral port 261 of the inner pipe and the stroke of the respective carriage or slide is such that at either extreme of this stroke the port or opening 261 will always be in communication with the interior of the outer telescopic pipe and thereby maintain a constant fluid connection between the inner and outer pipes. One end of the inner telescopic pipe communicates with a pressure fluid conducting pipe 264, and the outer telescopic pipe communicates with a pressure fluid conducting pipe 265, which last-mentioned pipes 264 and 265 form part of the conduit whereby the pressure fluid is conducted to and from one end of one of the cylinders of the hydraulic motors which operate the two sections of the expanding mechanism.

In the present case the pipe 265 leads to one end of one of these cylinders, and the pipe 264 leads to the source of fluid pressure supply and the valve mechanism which controls the same to and from the respective cylinder, as will presently appear.

Obviously the inner pipe might be mounted on the carriage or slide and the outer pipe mounted on the stationary frame, in which case the inner pipe would be connected with the respective motor cylinder and the outer pipe with the fluid pressure supply, this being a reversal of the organization shown in Figs. 26, 27 and 28.

60   *Hydraulic operating mechanism*

Although the operation of the various working parts of the machine, as heretofore set forth, may be effected by various means, it is preferable to accomplish this purpose by the hydraulic motors which have been referred to. In order to cause these hydraulic motors to operate in the manner described and in the proper sequence so that the various functions of feeding the drums or bodies, elevating the same into the proper position for engagement by the bead forming mechanism, moving the expander slides or carriages toward opposite ends of the drums, shifting the expanding shoes or dies of the two sections of the expanding mechanism successively into their opera-

tive and inoperative positions, withdrawing both expanding slides outwardly into their inoperative positions, and lowering the drum or body lifting mechanism, thereby completing the cycle of operations preparatory to again advancing the feeding mechanism for performing the next operation upon the drum, a valve mechanism is provided which includes a plurality of master valves and pilot valves whereby the admission and discharge of the pressure fluid to and from each hydraulic motor is automatically controlled by the action of moving parts of the machine, so that all of the functions are correlated and properly timed to produce the results which have been described.

In the preferred construction of this hydraulic operating mechanism the same is organized as follows:

The numerals 266, 267, 268, 269, 270 represent master valve mechanisms associated respectively with the motor cylinder 158 of the conveyer operating mechanism, the motor cylinder 174 of the drum lifting mechanism, the cylinders 205 of the motors which actuate the slides of the left and right hand sections of the expanding mechanism, the cylinder 220d of the motor which actuates the left hand expanding mechanism D, and the cylinder 220e of the motor which actuates the right hand expanding mechanism E. Each of these master valves is so constructed that in one position of its movable valve member high pressure actuating fluid, such as oil delivered from any suitable source by a pump 271, will be admitted to one end of the respective cylinder and force the piston therein away from said end, while the spent pressure fluid in the opposite end of this cylinder will be permitted to escape therefrom and be conducted back to a supply reservoir or tank 272 from which this pump again draws the actuating fluid and supplies the same to said cylinders. Upon shifting the movable member of each of these master valves alternately in opposite directions the pressure fluid derived from this pump or pressure source will be alternately admitted and exhausted from opposite ends of the respective motor cylinder, and thereby cause the respective pistons 159, 175, 206d, 206e, 221d and 221e in these cylinders to be reciprocated and actuate the parts which are connected therewith in the manner previously described.

Each of these master valves may be of the usual and well-known construction now commonly found on the market and used in steam engines, hydraulic motors and similar devices in which a piston or similar part is caused to reciprocate by alternately admitting a pressure medium and exhausting the spent pressure medium from opposite ends of the cylinder in which said part reciprocates, and a detailed illustration and description of such a valve device is therefore deemed unnecessary.

The fluid for operating the pistons of the hydraulic motors just referred to is supplied at a comparatively high pressure, and in Figs. 29-37 illustrating the valve mechanism of the various motors embodied in this machine, the conduits for conducting this high pressure fluid are shown somewhat larger than the conduits which are shown in these particular figures for the purpose of shifting the valves of this machine by means of fluid which is supplied under comparatively low pressure.

The outlet for the high pressure fluid of the pump 271 is indicated at 273 in Fig. 29 and the

outlet of this pump for the low pressure fluid. This master valve 288 has a movable control element for placing the low pressure liquid line 274 either in communication with or cutting the same off from the line 281, and this control element has a stem or rod 282, as shown in Figs. 2 and 30-37, which projects from opposite ends of the casing of the valve 288 in position to be engaged by either of two tappets 283, 284 which move with the piston 159 of the conveyer operating motor.

5 in the drawings by this numeral 273, and the main lines or conduits which conduct the actuating fluid under low pressure will be hereafter identified in this description and drawings by the reference numeral 274, but additional reference numerals will be employed as may be necessary for convenience in describing the construction and operation of this invention.

10 This pump may be operated by a motor of any suitable character, e. g. as shown in Fig. 38, 15 by means of an electric motor 275 which is provided on its driving shaft with a gear pinion 276 meshing with a gear wheel 277 on the shaft 278 of said pump.

15 The cylinder 205e of the motor which actuates 20 the slide carrying the section E of the bead expanding mechanism has its inner and outer ends connected with the corresponding ends of the cylinder 205d of the motor which shifts the slide of the bead expanding mechanism D so that when 25 the valve 268 is shifted in one direction or the other both pistons 206d and 206e will be moved inwardly and outwardly simultaneously by reason of the valve 268 establishing a connection between the corresponding ends of the cylinders of these 30 motors simultaneously either with the high pressure liquid line 273 or the high pressure return line pipe 285.

20 Each of the master valves 266, 267, 268, 269, 25 270 is actuated by liquid pressure which is supplied thereto from the low pressure liquid line of the pump through one or another of the pipes 274 forming in effect a continuation or branches of the low pressure liquid supply outlet 274, and as the shiftable controlling element or member 40 of each of these valves moves alternately into either one or the other of the two positions the ports or passages through these valves operate to alternately connect opposite ends of each of the cylinders 158, 174, 205d, 205e, 220e with said high 45 pressure liquid supply line for the purpose of reciprocating the piston in each of these cylinders and actuating the parts associated therewith.

50 The spent high pressure liquid from each of these master valves is carried back by return pipes 285 to the supply reservoir tank 212, and the low pressure liquid after having spent its force in shifting the pilot valves is carried back to this tank by low pressure return pipes 279. 55 In order to produce a high pressure in the high pressure conduits of this operating mechanism the latter may be connected with the outlet of the pump without any restriction, and a low pressure may be produced in the low pressure 60 conduits by introducing a pressure reducing valve of any suitable character into the low pressure line anywhere between the low pressure outlet of the pump and the various pilot valves which are supplied therefrom, such reducing valves being of common and ordinary construction and therefore do not require detailed illustration or description as to their 65 operation.

70 The numeral 280 represents a mechanically operated pilot valve which is adapted to be shifted by motion derived from the piston 159 of the conveyer feed motor and which is supplied by the piping 274 with low pressure actuating liquid and is connected by a pipe 281 with one end of the master valve 267 of the barrel lifting motor.

10 This master valve 288 has a movable control element for placing the low pressure liquid line 274 either in communication with or cutting the same off from the line 281, and this control element has a stem or rod 282, as shown in Figs. 2 and 30-37, which projects from opposite ends of the casing of the valve 288 in position to be engaged by either of two tappets 283, 284 which move with the piston 159 of the conveyer operating motor.

15 The numeral 286 represents a mechanically operated pilot valve associated with the piston 175 and adapted to control the flow of low pressure fluid from the pipe 274 either through a pipe 287 leading to one end of the master valve 266 or through a pipe 288 to one end of a liquid and motor operated valve 289 which is associated with the piston 206d of the motor which operates the slide of the left hand bead expanding mechanism D.

20 The numeral 290 represents a mechanically operated pilot valve which is associated with the piston 175 and adapted to control the flow of low pressure liquid by means of a pipe 291 to one end of the liquid and mechanically operated pilot valve 289, and receives low pressure liquid through a pipe 292 leading from one end of a mechanically operated pilot valve 293 and also to control the flow of low pressure liquid through a pipe 294 leading from the pilot valve 290 to the opposite end of the master valve 287.

25 The control elements of the valves 286 and 290 are provided with longitudinally movable stems or rods which are provided respectively with tappets 297 and 298, 299 and 300 which are 30 adapted to be engaged by a tappet 402 which moves with the piston 175, said tappet 402 operating to shift the control element of the valves 286 and 290 in one direction by engagement of the tappet 300 with the tappets 297, 298, and to 40 shift the control elements of these valves in the opposite direction by engagement of the tappet 402 with the other pair of tappets 299 and 300 of these valves.

45 The liquid and mechanically operated pilot valve is connected by means of a pipe 301 with one end of the casing of the liquid operated master valve 268 and also connected by a pipe 302 with two liquid and mechanically operated pilot valves 303d, 303e, which last-mentioned two 50 valves are associated with the pistons 221d and 221e of the hydraulic motors which operate the left and right hand sections D, E of the bead expanding mechanism. The liquid and mechanically operated valve 289 is connected with the pipe 291 and is moved in one direction by low 55 pressure liquid, and this valve element is moved in its opposite direction by a tappet 304 on the stem of this valve engaging with a tappet 306 which is carried by the piston 206d.

60 The opposite end of the casing of the pilot valve 293 is connected by a pipe 307 with the central part of a mechanically operated valve 308 associated with the piston 221e of the motor which actuates the section E of the bead expanding mechanism. The control element of the valve 293 is provided with two spaced tappets 310, 311 which are adapted to be engaged alternately by the tappet 306 of the piston 206d.

65 The liquid and mechanically operated pilot valve 303d has its casing connected at one end by means of a pipe 312 with one end of the casing of the master valve 268, and its opposite end is connected by means of a pipe 313 with the opposite end of the casing of the valve 269, and is 70 75

also connected by means of a pipe 314 with a mechanically operated pilot valve 315 which is associated with the piston 221e of the motor which operates the section E of the expanding mechanism, and the central part of the casing of the valve 303d is connected by means of a pipe 316 with one end of a liquid and mechanically operated pilot valve 303e which is associated with said piston 221e.

10 The opposite end of the casing of the valve 303e is connected by means of a pipe 318 with the opposite end of the liquid operated master valve 268, while the central part of the casing of the valve 303e is connected by means of a pipe 319 with one end of the mechanically operated pilot valve 308. The control element of the pilot valve 303d is provided with a tappet 320 which is adapted to be engaged by a tappet 321d connected with the piston 221d; and the control element 15 of the valve 303e is adapted to be shifted by engagement of its tappet 321e with a tappet 322 of the piston 221e. The last-mentioned piston is also adapted to shift the control members of the valves 308 and 315 at opposite ends of its 20 stroke by engaging during its outward stroke with tappets 323, 324 on the control members of valves 315 and 308, and by engaging during its forward stroke with tappets 325, 326 which are connected respectively with the control elements of the valves 315, 308.

25 The master valve 270 of the right hand expander motor cylinder 220e communicates by pipe 317 with the mechanically operated valve 315 associated with the piston 221e of the cylinder and one end of the pilot valve 308 communicates by pipe 327 with the master valve 266.

30 Figures 30-37 illustrate diagrammatically the main positions which the several valves of this machine assume during a complete cycle of operations, and in these figures the solid or dark pipes indicate those containing active pressure fluid, while the light or unshaded pipes indicate those in which the pressure fluid is not active.

35 In Fig. 30 the various valves occupy a position which they assume when the barrel drum or body conveying mechanism is effecting a forward feeding stroke, and at this time the operation of the valves and the flow of pressure fluid for performing the required functions is as follows:

40 The position of the control element of the master valve 266 is assumed to have been shifted by pressure derived from the low pressure pipe 287 so as to cause the fluid from the high pressure line, represented at 273, to be conducted to the right hand end of the cylinder 158 while the spent pressure medium is discharged through the left end of this cylinder, thereby causing the piston 159 therein to be moved toward the left, together with the tappets 284 and 283.

45 During this movement of the piston 159 a barrel drum which has been placed upon the track of the machine will be fed forward by the conveyer mechanism, and during the last portion of the movement of this piston in this direction the tappet 284 will engage with the right hand end of the valve stem 282 and push the valve element therein toward the left, as indicated in Fig. 31. Low pressure liquid is now permitted to pass through the casing of the mechanically operated pilot valve 280 from the low pressure line 274 through the pipe 281 to one end of the casing of the liquid operated master valve 267, thereby causing the rear end of the cylinder 174 of the drum lifting motor to be connected with the high pressure liquid line, and the

5 upper end of the cylinder to be connected with the return pipe 285, see Fig. 29, whereby the piston 175 in this cylinder is moved forwardly and the drum lifting mechanism is caused to engage a drum and elevate the same into alignment with the two sections of the expanding mechanism.

10 When the piston 174 effects the last portion of its forward stroke its tappet 402 engages the tappets 298, 300 of the control elements of the 15 mechanically operated pilot valves 286 and 280 and shifts these elements into the position indicated in Fig. 32. In this shifted position of the valves 286, 280 low pressure fluid is permitted to pass from the low pressure line 274 through 15 the valve 286 and pipe 288 to the central part of the liquid and mechanically operated pilot valve 289, low pressure fluid is permitted to pass from the low pressure pipe 274, pilot valve 293, pipe 292, valve 290, line 294 to the opposite end 20 of the liquid operated master valve 267, but low pressure fluid is permitted to pass through the casing of the valve 289 and into one end of the liquid operated master valve 268, and thereby shift the control element therein so that the high 25 pressure liquid pipe 273 is connected with the outer or rear ends of the cylinders 205d and 205e, whereby both pistons 206d and 206e are moved simultaneously forwardly toward each other for the purpose of moving forwardly or toward each 30 other the two slides 202d, 202e which carry the two sections D and E of the bead forming mechanism.

35 As the expander slides effect their inward movement in accordance with the position of the valves shown in Fig. 32 and the expander mechanisms are moved into the barrel drum, the tappet 306 of the piston 206d engages the pilot valve tappets 304, 311 and moves the control elements of the mechanically operated pilot valve 293 and 40 the liquid and mechanically operated pilot valve 280 from the position shown in Fig. 32 to the position shown in Fig. 33. When thus shifted the valve 293 cuts off the low pressure fluid from the pipe 292 and connects low pressure 45 274 in the pilot valve 293 with the pipe 301 leading from the valve 293 to the mechanically operated pilot valve 308, thence to the liquid and mechanically operated pilot valve 303e, thence through pipe 316 to the liquid and mechanically operated valve 303d, and thence to one end of the master high pressure valve 268, thereby causing the piston 221d to move forwardly and spread the dies of the expander section D, while the dies of the expander section E remain in their contracted 50 position.

55 During the last part of the forward movement of the piston 221d the tappet 321d thereof engages the tappet 320 so as to shift the valve element of the pilot valve 303d from the position shown in Fig. 33 to the position shown in Fig. 34, whereby the piston is caused to immediately move backwardly and contract the dies of expander D due to the valve 303d cutting off the low pressure fluid from the pipe and instead connecting the same with the pipe 313 leading to the opposite end of the master valve 268 and causing the course of the high pressure fluid to be reversed to the front end of the cylinder 220d. At the same time low pressure fluid flows from the pilot valve 303d through the pipe 314 to the mechanically operated valve 315, thence through the pipe 317 to one end of the master valve 270 whereby the control element in the latter is shifted so that the high pressure fluid is directed 75

thereby into the outer or rear end of the cylinder 220e and the piston 211e therein is moved forward for spreading the dies of the expander E within the drum.

- 5 As the piston 211e completes its forward movement the tappet 322 thereof engages the front tappets 326 and 325 of the control elements of pilot valves 308 and 315 whereby these elements are shifted from the position shown in Fig. 34
 10 to the position shown in Fig. 35. This causes the piston 211e to immediately move backwardly due to the control element in the master valve 270 being reversed and the high pressure fluid is admitted to the front end of the cylinder 220e
 15 and contracts the dies of the expander E, and the control element of the pilot valve 308 is shifted so as to shut the pipe 319.

At the end of the forward movement of the piston 211e the same also engages the tappet 321e 20 of the pilot valve 303e whereby the control element of the same shuts off the low pressure fluid from the pipes 313, 314 and 316. During the last part of the backward movement of the piston 211e its tappet 322 engages the rear tappets 324 and 25 323 of the control elements of the pilot valves 308 and 315 and shifts the same from the position shown in Fig. 35 to the position shown in Fig. 36, whereby the pilot valve 308 shuts off the pipe 327 leading from the pilot valve 308 to the master 30 30 valve 266 of the conveyer operating motor, and again connects the pipe 307 coming from the pilot valve 293 with the pipe 319 leading to the pilot valve 303e.

At this time the control element of the pilot 35 valve 303e is in a position to connect pipe 319 with pipe 318 leading to one side of the master valve 268 of the cylinders 205d, 205e of the motors which actuate the slides carrying the expanders D, E, whereby the control element of the 40 valve 268 is shifted so as to admit the high pressure liquid to the front ends of the cylinders 205d and 205e and cause the pistons 206d, 206e therein to be moved backwardly as indicated in Fig. 36, and thus carry both expander supporting slides 45 into an inoperative position relative to the barrel drum.

During the last part of the backward movement of the expander slide piston 206d the tappet 306 thereof engages the tappet 310 of the control 50 element of the pilot valve 293 and shifts the latter from the position shown in Fig. 36 to the position shown in Fig. 37, thereby shutting off the low pressure fluid pipe 307 leading from the valve 293 to the valve 308 and connecting the low pressure fluid supply with the pipe 292 leading to the valve 290. The control element of the latter at this time is in such position that the pipe 292 is connected with the pipe 294 leading to the master valve 267 of the drum lifting motor, 60 whereby the control element in the last-mentioned valve is shifted so as to admit high pressure fluid into the front end of the cylinder 174, as shown in Fig. 37, and cause the piston 175 therein to be moved backwardly for lowering the 65 barrel drum from the beading mechanism onto the conveyer mechanism.

During the last part of the backward movement of the piston 175 of the drum lifting motor the tappet 402 thereof engages the rear 70 tappets 297, 299 of the control elements of the pilot valves 286, 290 whereby the connections through the latter are changed from the position shown in Fig. 37 to the position shown in Fig. 30. In this changed position the low pressure fluid 75 conducting pipe 288 leading to the pilot valve

289 is shut off and the low pressure fluid is admitted to the pipe 287 leading to one side of the master valve 266 which controls the admission of high pressure fluid to the cylinder 158 of the conveyer operating mechanism. High pressure fluid is admitted at this time into that end of the cylinder 158 which will cause the piston 159 therein to move in the direction for causing the conveyer mechanism to move forwardly, as shown in Fig. 30.

During the backward movement of the piston 175 of the drum lifting mechanism the tappet 402 of the same also engages the rear tappet 299 and shifts the control element of the valve 290 in the direction for cutting off the low pressure fluid from the pipe 294 leading to one end of the master valve 267 controlling the flow of pressure fluid to the cylinder 174 so that the drum lifting motor for the time being remains at rest. The pipe 292 which has previously been placed 20 in communication with the low pressure fluid supply by the pilot valve 293 during the return movement of the expander supporting slides, is now connected with the pipe 291 leading to the pilot valve 289 and moves the control element 25 in the latter backwardly together with its tappet 304, and thus cutting off communication between the fluid pressure pipe 288 and the pipes 301, 302 leading, respectively, to the slide motor master valve 268 and the pilot valves 303d, 303e 30 associated with the expander spreading and contracting motors.

When the pilot valve 289 is operated by fluid pressure derived from the pipe 291 for shifting the same into the position shown in Fig. 32 the 35 control element of the valve, the pipe 288 which has previously been placed in communication with the fluid pressure supply through the pilot valve 286 by the forward movement of the drum lifting piston 175, is now connected through the 40 pilot valve 289 with the pipe 301 leading to the master valve of the expander slides for moving the same forward, and also connected by the pipes 302 leading to the pilot valves 303d and 303e, for moving their tappets 320 and 321e toward the 45 tappets 321d, 322 of the expander spreading and contracting pistons 221d and 221e, as shown in Fig. 32.

The master and pilot valve actuating means shown diagrammatically in Figs. 30-37 are 50 specifically constructed as follows:

As shown in Fig. 2, the tappets 283, 284 of the conveyer motor are preferably constructed in the form of screws which are mounted on arms 400, 401 carried by the piston rod 161 and the gear 55 rack 162 and thereby permits the time of shifting the control element 282 of the pilot valve 288 to be adjusted as required.

In actual practice the motion of the piston 175 of the drum lifting motor is transmitted to 60 the control elements 295, 296 of the pilot valves 286, 290 by the mechanism which is best shown in Figs. 6, 14 and 18 and which includes a rock arm 403 connected with the rock shaft 185 and a swivel 404 connecting the rock arm 403 with 65 the tappet 402. In this form the control elements or members 295, 296 are connected in tandem and the tappets 297, 298 have the form of a collar or nut moving with these control members and arranged on one side of the tappet 402, while the 70 tappets 299, 300 have the form of another nut or collar moving with said control members and arranged on the opposite side of the tappet 402.

The actual operating mechanism of the control elements or members 305, 309 of the pilot valves 75

288, 293 is best shown in Figs. 2, 24 and 25 and is constructed as follows:

As there shown the control members or elements 305 and 308 of the pilot valves 288, 293 are arranged in line and a tappet 306c is provided which is connected with the control 309 but only abuts against the opposing end of the other control element 305. The tappet 306c is provided on opposite sides with tappet faces 310a, 311a 10 which are the equivalent of the tappets 310, 311 of the diagrammatic representation.

The adjacent gear rack 214 of the slide operating piston 206d is provided with spaced tappets 306a, 306b having preferably the form of 15 adjustable screws which are adapted to engage alternately with opposite tappet faces 310a, 311a of the tappet 306c. When the gear rack 214 moves forwardly with the piston 206d, or from left to right in Fig. 24, the tappet 306c associated 20 therewith engages with the face 310a of the tappet 306c during the last part of the stroke of this piston in this direction, and thereby shifts the control elements 309, 305 mechanically in the same direction and producing the same effect as 25 when the piston 206d in Figs. 30-37 moves from left to right and its tappet 306 engages the tappets 304 and 311.

During the subsequent backward movement of the piston 206d the other tappet 306b engages 30 the opposite face 311a of the tappet 306c and moves the same with the control element 309 only from right to left during the last part of this stroke of the piston, thereby producing an effect corresponding to that produced by engagement 35 of the piston tappet 306 with the tappet 310 in the diagrammatic representation in Figs. 30-37. The control element 305 of the pilot valve 288 in Fig. 24 will also be moved backward by liquid pressure supplied through the pipe 291 in 40 the same manner in which this is done in Figs. 30-37.

The practical embodiment of the means for actuating the pilot valve 303d are best shown in Figs. 3, 6 and 23 and as there shown the same is 45 organized as follows:

The numeral 500 represents a longitudinal horizontal rock shaft journaled on the rear side of the main frame adjacent to the left hand carriage or slide 202d which supports the expander 50 mechanism D and provided at one end with a tappet lever 501 which carries at its lower end a tappet 502. A horizontally turning rock lever or plate 503 is pivoted on the main frame and is adapted to be engaged at one end by the tappet 55 502 while its opposite end is adapted to engage with the tappet 320 of the control element of the pilot valve 303d mounted on the adjacent part of the main frame. A rocking movement is imparted to the shaft 500 by motion derived from 60 the reciprocation of the left hand carriage or slide 202d through the medium of an upright rock shaft 504 journaled on the slide 202d and provided at its upper end with an inwardly projecting arm 505 of an elbow lever which is connected by a coupling 506 with the adjacent rod of 65 the piston 221d in the left hand slide cylinder 220d, while the outer arm 507 of this elbow is connected by a universal joint 508 with a rock arm 509 projecting upwardly from the rock shaft 500, as shown in Figs. 1 and 3. The rock arm 509 is so mounted on the shaft 500 that these parts are compelled to turn together but the rock arm 509 is compelled to slide lengthwise on the shaft and to move with the slide 202d, this being 70 preferably accomplished by means which include 75

making this shaft square in cross section and passing the same through a correspondingly shaped opening in the hub of the arm 509.

As the carriage or slide 202d moves forwardly and backwardly the rock arm 509 slides lengthwise on the shaft 500, and therefore always maintains a motion transmitting connection between the rod of the piston 221d and the lever 501 during this time regardless of the position of the respective carriage. After the slide 202d has 10 reached the forward end of its stroke the left hand expander piston 221d moves forwardly for spreading the beading dies or shoes connected therewith and at the same time motion is transmitted from the rod of this piston through the 15 medium of the inner rock arm 505, outer rock arm 507, upper sliding rock arm 508, rock shaft 500, non-sliding rock arm 501, tappet 320, and rock lever 503 to the tappet 320 of the controlling element of the pilot valve 303d, thereby setting 20 the same as described with reference to Figs. 30-37, preparatory to again reversing the position of the pilot valve 303d by fluid pressure supplied by the pipe 302.

The practical means for operating the pilot 25 valves 303e, 315 and 308 are best shown in Figs. 2, 4, 6, 20, 21 and 22 and are constructed as follows:

These pilot valves are mounted in a longitudinal row on the lower right hand part of the main 30 frame and have the stems or spindles 321e, 603, 604 of their controlling members or elements projecting forwardly. The stem 603 is the equivalent of the tappets 326 and 324 in the diagrammatic representation in Figs. 30-37, while the 35 spindle 604 is the equivalent of the tappets 325 and 323 in the same figures. The valve stems 603, 604 are connected by a cross bar 605 so that these controlling members are compelled to move in unison, but the stem 321e of the valve 303e is 40 movable independently of the stems 603, 604. When the valve stems 603, 604 are moved forwardly the valve stem 321e is compelled to move backwardly by a rocker lever or plate 606 pivoted to swing horizontally on the main frame and 45 having one arm in position to be engaged by the cross bar 605 and its other end in position to be engaged by the front end of the valve stem 321e.

The cross bar 605 is adapted to be moved forwardly and backwardly together with the valve 50 stems connected therewith by motion derived from the reciprocating carriage or slide 202e which carries the right hand or second expander. These transmitting means in their preferred form comprise a horizontal longitudinal rock shaft 607 55 journaled in bearings on the front side of the right hand end of the main frame and provided with a depending rock arm 608. At its lower end the latter is provided with two tappets 609, 610 preferably in the form of screws which are adapted to 60 engage opposite sides of the cross bar 605. The numerals 612, 613 represent the inner and outer arms of an elbow or bell crank lever which is pivoted to swing horizontally on the slide or carriage 202e of the right hand expander, the inner 65 arm 612 being connected by a coupling 614 with the rod of the piston 321e, while the outer arm 613 is connected by a universal coupling 615 with a rock arm 616 projecting upwardly from the rock shaft 607. The rock arm 616 has a square 70 opening which receives the body of the shaft 607 of square form in cross section, thereby compelling the shaft 607 and arm 616 to turn together but permitting the arm to slide on this shaft. The arm 616 is compelled to move length- 75

wise with the slide 202e by a bracket 617 on the slide 202e.

The driving connection between the piston of the expander motor pistons 221d and 221e and pilot valves operated thereby are identical so far as the rock shaft 500 and 607, the rock levers 501, 608, bell crank levers 612, 613, rock arms 509 and 616, swivel connections 508 and 615, and brackets 617 are concerned, and only those on the right hand side of the machine have therefore been fully illustrated.

During the forward or inward stroke of the slide 202e the arm 616 moves lengthwise on the shaft 607 without disturbing the operative connection between the piston 221e and the lever 608, and while the slide is in its innermost position the piston 221e moves forwardly and backwardly for spreading and contracting the beading dies or shoes of the second or right hand expander at the same time the lever 608 first moves outwardly from the full line position to the dotted line position in Fig. 22, whereby the stems of the valves 308 and 315 are moved outwardly mechanically and the stem of the valve 303e is moved inwardly through the rocker lever 606, but during the reverse movement of this lever only the stems of the valves 308, 315 are moved backwardly mechanically, the backward movement of the stem of the valve 303e being effected by fluid pressure.

If during the forward or inward movement of the expander carrying slides or carriages any jamming action should occur due to disarrangement of the drums or other causes, means are provided for instantly reversing the movement of the slides and correcting the difficulty. This is preferably accomplished by providing a hand operated lever 700 which is pivoted on the main frame and connected with one end of the stem or spindle 701 of the controlling element or member of the master valve 268, as shown in Fig. 2. Upon turning this lever 700 to the right movement of the pistons 206d, 206e is instantly reversed and the expanding devices are withdrawn from the drum. As the expander slides effect the last part of their outward or backward movement a restoring tappet 702 engages with the reversing lever 700, as shown in Figs. 24 and 25, and causes this lever to be automatically returned to its normal position in which the valve 268 has again been set so that the same admit the pressure medium at the right time to opposite ends of the cylinders 205d, 205e and discharge the spent pressure fluid therefrom alternately, for restoring the normal running of the machine.

For the purpose of starting and stopping the machine as a whole a main valve 703 is provided in the fluid pressure supply pipes at the pump, which valve is preferably operated by a hand lever 704, as shown in Figs. 1, 38 and 39.

I claim as my invention:

1. A conveyor mechanism for moving bodies to be worked upon to and from an operating station including a track over which said bodies are moved, a feeding frame reciprocating lengthwise of said track, and feeding means movably mounted on said frame and adapted to project upwardly from said frame and operatively engage the bodies during the forward movement of the frame and to be deflected downwardly out of the path of said bodies during the backward movement of the frame, each of said feeding means having a dog pivoted at its lower end on said frame and provided with an arm, a shifting rod connected with said arm, a guide for said rod, a spring interposed between said guide and a shoulder on said rod and operating to hold the dog yieldingly in its operative position, and a stop for limiting the movement of said dog under the action of said spring.

2. A conveyor mechanism for moving bodies to be worked upon to and from an operating station including a track over which said bodies are moved, a feeding frame reciprocating lengthwise of said track, and feeding means movably mounted on said frame and adapted to project upwardly from said frame and operatively engage the bodies during the forward movement of the frame and to be deflected downwardly out of the path of said bodies during the backward movement of the frame, each of said feeding means having a dog pivoted at its lower end on said frame and provided with an arm, a shifting rod connected with said arm, a guide for said rod, a spring interposed between said guide and a shoulder on said rod and operating to hold the dog yieldingly in its operative position, and a stop for limiting the movement of said dog under the action of said spring.

3. A conveyor mechanism for moving bodies to be worked upon to and from an operating station including a track over which said bodies are moved, a feeding frame reciprocating lengthwise of said track, and feeding means movably mounted on said frame and adapted to project upwardly from said frame and operatively engage the bodies during the forward movement of the frame and to be deflected downwardly out of the path of said bodies during the backward movement of the frame, each of said feeding means having a dog pivoted at its lower end on said frame and provided with an arm, a shifting rod connected with said arm, a guide for said rod, a spring interposed between said guide and a shoulder on said rod and operating to hold the dog yieldingly in its operative position, and a stop for limiting the movement of said dog under the action of said spring, and a plate adjustably connected with said frame and supporting said dog, guide and stop.

4. A conveyor mechanism for moving bodies to be worked upon to and from an operating station including a track over which said bodies are moved, a feeding frame reciprocating lengthwise of said track, and feeding means movably mounted on said frame and adapted to project upwardly from said frame and operatively engage the bodies during the forward movement of the frame and to be deflected downwardly out of the path of said bodies during the backward movement of the frame, and detent means for permitting the bodies to move forwardly with said frame but preventing backward movement of the bodies with said frame, and including a detent dog pivoted at its lower end on a fixed support and provided with an arm, a shifting rod connected with said arm, a guide for said rod, a spring interposed between said guide and a shoulder on said rod, and a stop for limiting the movement of said dog under the action of said spring.

5. A conveyor mechanism for moving bodies to be worked upon to and from an operating station including a track over which said bodies are moved, a feeding frame reciprocating lengthwise of said track, and feeding means movably mounted on said frame and adapted to project upwardly from said frame and operatively engage the bodies during the forward movement of the frame and to be deflected downwardly out of the path of said bodies during the backward movement of the frame, detent means for permitting the bodies to move forwardly with said frame but preventing backward movement of the bodies with said frame and including a detent dog pivoted at its lower end on a fixed support and provided with an arm, a shifting rod connected with said arm, a guide for said rod, a spring interposed between said guide and a shoulder on said rod, a stop for limiting the movement of said dog under the action of said spring, and a plate adjustably secured to said track and supporting said dog, guide and stop.

6. A conveyor mechanism for moving bodies to be worked upon to and from an operating station including a track over which said bodies move, detent means for permitting the bodies to move forwardly but preventing backward movement thereof, feeding means which effect forward

- movement of said bodies, and stop means which at times hold said bodies against forward movement and which are movable into and out of the path of said bodies.
- 5 6. A conveyor mechanism for moving bodies to be worked upon to and from an operating station including a track over which said bodies move, detent means for permitting the bodies to move forwardly but preventing backward movement thereof, feeding means which effect forward movement of said bodies, and stop means which at times hold said bodies against forward movement and which include a vertically swinging stop dog pivoted at its lower end and provided with an arm, a shifting rod connected with said arm, a guide for said rod, a spring interposed between said guide and a shoulder on said rod and operating to yieldingly hold said dog in the path of said bodies, and a stop for limiting the movement of said dog under the action of said spring.
- 10 7. A conveyor mechanism for moving bodies to be worked upon to and from an operating station, including a track over which said bodies move, detent means for permitting the bodies to move forwardly but preventing backward movement thereof, feeding means which effect forward movement of said bodies, stop means which at times hold said bodies against forward movement, and which include a vertically swinging stop dog pivoted at its lower end and provided with an arm, a shifting rod connected with said arm, a guide for said rod, a spring interposed between said guide and a shoulder on said rod and operating to yieldingly hold said dog in the path of said bodies, a stop for limiting the movement of said dog under the action of said spring, and a plate adjustably mounted on said track and supporting said dog, guide and stop.
- 15 8. A conveyor mechanism for moving bodies to be worked upon to and from an operating station, including a track over which said bodies move, detent means for permitting the bodies to move forwardly but preventing backward movement thereof, feeding means which effect forward movement of said bodies, stop means which at times hold said bodies against forward movement, and depressing means whereby said stop means are lowered into an inoperative position and permit the bodies to move forwardly.
- 20 9. A conveyor mechanism for moving bodies to be worked upon to and from an operating station, including a track over which said bodies move, detent means for permitting the bodies to move forwardly but preventing backward movement thereof, feeding means which effect forward movement of said bodies, stop means which at times hold said bodies against forward movement, and depressing means whereby said stop means are lowered into an inoperative position and permit the bodies to move forwardly, said depressing means operating on said stop means while the feeding means are effecting an idle return movement.
- 25 10. A conveyor mechanism for moving bodies to be worked upon to and from an operating station, including a track over which said bodies move, detent means for permitting the bodies to move forwardly but preventing backward movement thereof, feeding means which effect forward movement of said bodies over said track and which include a longitudinally reciprocating frame and feeding dogs yieldingly mounted on said frame and adapted to engage the rear side of said bodies during the forward movement of said
- frame and to clear said bodies during the backward movement of said frame, stop means which at times arrest the forward movement of said bodies and which includes stop dogs pivoted on said tracks and yieldingly held in an elevated operative position in the path of said bodies, and depressing plates mounted on said frame and adapted during the backward movement of said frame to engage said stop dog and move the same downwardly out of the path of said barrel bodies.
- 30 11. A conveyor mechanism for moving bodies to be worked upon to and from an operating station, including a track over which said bodies move, detent means for permitting the bodies to move forwardly but preventing backward movement thereof, feeding means which effect forward movement of said bodies over said track and which include a longitudinally reciprocating frame and feeding dogs yieldingly mounted on said frame and adapted to engage the rear side of said bodies during the forward movement of said frame and to clear said bodies during the backward movement of said frame, stop means which at times arrest the forward movement of said bodies and which includes stop dogs pivoted on said tracks and yieldingly held in an elevated operative position in the path of said bodies, depressing plates mounted on said frame and adapted during the backward movement of said frame to engage said stop dog and move the same downwardly out of the path of said barrel bodies, and adjusting plates carrying said depressing plates and each adjustably connected with said reciprocating frame.
- 35 12. A conveyor mechanism for moving bodies to be worked upon to and from an operating station including a longitudinally reciprocating frame provided with dogs for engaging said bodies, and means for reciprocating said frame comprising a longitudinal gear rack arranged on said frame, a gear wheel meshing with said frames, a horizontal oscillating shaft carrying said gear wheel, an upright intermediate shaft, intermeshing bevel gear wheels secured respectively to said upright and horizontal shafts, a gear pinion connected with said upright shaft, a transverse gear rack meshing with said gear pinion, and a hydraulic motor for operating said gearing including a power cylinder, a piston arranged in said cylinder and connected with the last-mentioned gear rack, and a valve mechanism for admitting live pressure liquid and discharging spent pressure alternately to and from opposite ends of said cylinder.
- 40 13. A conveyer mechanism for moving a body to be worked upon relatively to operating means which operate on said body, said conveyer means including, longitudinal conveyer means for moving said body to and from said operating means, and lateral shifting means for moving said body laterally relatively to said conveyer means and into a position to be operated upon by said operating means.
- 45 14. A conveyer mechanism for moving a body to be worked upon relatively to operating means which operate on said body, said conveyer means including, a horizontal longitudinal conveyer for moving said body to said operating means, and a shifting mechanism for raising said body from said conveyer and presenting the same to said operating means and again lowering the same onto said conveyer.
- 50 15. A conveyer mechanism for moving a body to be worked upon relatively to operating means which operate on said body, said conveyer means

- including, a horizontal longitudinal conveyer for moving said body to said operating means, and a lifting mechanism for raising said body from said conveyer and presenting the same to said operating means, including a lifting frame having saddle means for engaging the underside of the body, a guide for controlling said frame in its vertical movement, and a motor operatively connected with said frame for raising and lowering the same.
16. A conveyer mechanism for moving a body to be worked upon relatively to operating means which operate on said body, said conveyer means including, a horizontal longitudinal conveyer for moving said body to said operating means, and a lifting mechanism for raising said body from said conveyer and presenting the same to said operating means, including a lifting frame having saddle means for engaging the underside of the body, a guide for controlling said frame in its vertical movement, a motor operatively connected with said frame for raising and lowering the same, and adjusting means forming part of the operative connection between said motor and said frame for varying the stroke of the latter.
17. A conveyer mechanism for moving a body to be worked upon relatively to operating means which operate on said body, said conveyer means including, a horizontal longitudinal conveyer for moving said body to said operating means, and a lifting mechanism for raising said body from said conveyer and presenting the same to said operating means, including a lifting frame having saddles adapted to engage with the underside of said body adjacent to opposite ends thereof, upright bars connected with said saddles, horizontal bars connecting said upright bars, a vertically movable slide connected with said horizontal bars, a vertical guide on which said slide runs, and a motor operatively connected with said slide.
18. A conveyer mechanism for moving a body to be worked upon relatively to operating means which operate on said body, said conveyor means including, a horizontal longitudinal conveyer for moving said body to said operating means, and a lifting mechanism for raising said body from said conveyer and presenting the same to said operating means, including a lifting frame having saddles adapted to engage with the underside of said body adjacent to opposite ends thereof, upright bars connected with said saddles, horizontal bars connecting said upright bars, a vertically movable slide connected with said horizontal bars, a vertical guide on which said slide runs, a motor for operating said slide, and an adjustable mechanism for transmitting motion from said motor to said slide including a longitudinally reciprocating rod actuated by said motor, a driving rock lever having an operating arm connected with said rod, and an adjusting arm, a driven elbow rock lever having an operating arm connected with said slide and an adjusting arm, the fulcrum of said levers being out of line with each other, and a connection between said adjusting arms which is adjustable toward and from the axes of the same.
19. A conveyer mechanism for moving a body to be worked upon relatively to operating means which operate on said body, said conveyer means including, a horizontal longitudinal conveyer for moving said body to said operating means, and a lifting mechanism for raising said body from said conveyer and presenting the same to said operating means, including a lifting frame having saddles adapted to engage with the underside of said body adjacent to opposite ends thereof, upright bars connected with said saddles, horizontal bars connecting said upright bars, a vertically movable slide connected with said horizontal bars, a vertical guide on which said slide runs, a motor for operating said slide, and an adjustable mechanism for transmitting motion from said motor to said slide including a longitudinally reciprocating rod actuated by said motor, a driving rock lever having an operating arm connected with said rod, and an adjusting arm, a driven elbow rock lever having an operating arm connected with said slide and an adjusting arm, the fulcrum of said levers being out of line with each other, and a connection between said adjusting arms which is adjustable toward and from the axes of the same.
20. A conveyer mechanism for moving a body to be worked upon relatively to operating means which operate on said body, said conveyer means including, a conveyer for moving said body to said operating means, means for elevating said body from the conveyer at the operating means and again lowering the same onto said conveyer and having parts engaging with the underside of the body, and retaining means adapted to be engaged by the body in the elevated position of the latter.
21. A conveyer mechanism for moving a body to be worked upon relatively to operating means which operate on said body, said conveyer means including, a conveyer for moving said body to said operating means, means for elevating said body at the operating means and having parts engaging with the underside of the body, and retaining means adapted to be engaged by the body in the elevated position of the latter, including a stationary support, a stop adapted to be engaged by the upper side of the body, a rod projecting upwardly from said stop, lugs arranged on said support and receiving said rod, a collar arranged on said rod between said lugs, and a set screw for adjustably securing said collar to said rod.
22. A conveyer mechanism for moving a sheet metal barrel body relative to means for forming beads on the body, comprising, a conveyer for moving said body to said beading means, and guiding means adapted to be engaged by opposite ends of said body for directing the same properly relatively to said beading means.
23. A conveyer mechanism for moving a sheet metal barrel body relative to means for forming beads on the body, comprising, a conveyer for moving said body to said beading means, and guiding means adapted to be engaged by opposite ends of said body for directing the same properly relatively to said beading means, and comprising two guide plates having parallel rear parts for locating said body and forwardly converging rear parts which are adapted to engage with the ends of the body and direct the same between said parallel parts, and means for adjusting each of said plates relative to an end of said body including a stationary support, a clamping plate, screws connecting said support and clamping plate, and an adjusting arm carrying each guide

- plate and secured between said support and clamping plate.
24. A conveyer mechanism for moving sheet metal barrel drums relative to means for forming beads on said drums, comprising conveyer means for feeding barrel drums, lifting means for raising said drums from said conveyer to said beading means, and hydraulic power means for actuating said conveyer means, and lifting means.
- 10 25. A conveyer mechanism for moving sheet metal barrel drums relative to beading means for forming beads on said drum; comprising a conveyer for feeding barrel drums, a hydraulic motor for actuating said conveyer, a lifter for raising said drums from said conveyer, and a hydraulic motor for actuating said lifter and controlled by motion derived from said conveyer actuating motor.
- 20 26. A conveyer mechanism for moving sheet metal barrel drums relative to expanding means adapted to form beads successively on opposite ends of each of said drums, comprising a conveyer for feeding barrel drums, a hydraulic motor for actuating said conveyer, a lifter for raising each 25 of said drums from said conveyer and lowering the same, a hydraulic motor for actuating said lifter, and a valve mechanism associated with said conveyer motor, and lifter motor, and operating to cause said motors to successively and 30 repeatedly move the conveyer forwardly, raise the lifter, and lower said lifter preparatory to beginning another cycle of operations.
27. A conveyer mechanism for moving sheet metal barrel drums relative to expanders which are adapted to form beads successively on opposite ends of each of said drums, comprising a conveyer for feeding barrel drums, a hydraulic motor for actuating said conveyer, a lifter for raising each of said drums from said conveyer 40 and lowering the same, a hydraulic motor for actuating said lifter, and valve mechanism associated with said conveyer motor, and lifter motor, and operating to cause said motors to successively and repeatedly move the conveyer forwardly, raise the lifter, and lower said lifter 45 preparatory to beginning another cycle of operations, each of said motors having a power cylinder, a piston which is reciprocated therein by admitting pressure fluid alternately into opposite ends of said cylinder, and a reversing master valve controlling the admission and discharge of pressure liquid to and from said cylinder, said conveyer motor having a mechanically operated pilot valve which is shifted by 50 said conveyer motor and communicates with the master valve of the lifter motor, said lifter motor having two mechanically operated pilot valves which are actuated by said lifter motor and one of which communicates with the master valve of the conveyer motor.
- 60 28. A conveyer mechanism for moving sheet metal barrel drums to beading means for producing circumferential beads on opposite ends of each of said drums, said conveyer mechanism including a track over which said drums are conveyed to said beading means, and which has rails adjustable laterally relatively to the path of the drums to suit drums of different length.
29. A conveyer mechanism for moving sheet metal barrel drums to beading means for producing circumferential beads on opposite ends of each of said drums, said conveyer mechanism including a track over which said drums are conveyed to said beading means and which has rails adjustable laterally relatively to the path of the drums to suit drums of different length, and drum propelling means including a plurality of longitudinal feeding bars which are adjustable laterally relative to the path of the drums.
- 10 30. A conveyer mechanism for moving sheet metal barrel drums to beading means for producing circumferential beads on opposite ends of each of said drums, said conveyer mechanism including a track over which said drums are conveyed to said beading means and which has rails adjustable laterally relatively to the path of the drums to suit drums of different length, drum propelling means including a plurality of longitudinal feeding bars which are 15 adjustable laterally relative to the path of the drums, and yielding dogs mounted on said bars and adapted to engage with the front and rear side of each drum.
31. A conveyer mechanism for moving sheet metal barrel drums to beading means for producing circumferential beads on opposite ends of each of said drums, said conveyer mechanism including a track over which said drums are conveyed to said beading means and which has rails adjustable laterally relatively to the path of the drums to suit drums of different length, drum propelling means including a plurality of longitudinal feeding bars which are 20 adjustable laterally relative to the path of the drums, and yielding dogs mounted on said bars and adapted to engage with the front and rear side of each drum.
- 35 32. A conveyer mechanism for moving sheet metal barrel drums to beading means for producing circumferential beads on opposite ends of each of said drums, said conveyer mechanism including a track over which said drums are conveyed to said beading means and which has rails adjustable laterally relatively to the path of the drums to suit drums of different length, drum propelling means including a plurality of longitudinal feeding bars which are 30 adjustable laterally relative to the path of the drums, yielding dogs mounted on said bars and adapted to engage with the front and rear side of each drum, guide rollers for said feeding bars, a laterally adjustable bracket carrying said rollers, a gear rack connected with said bracket, 35 and a gear pinion meshing with said gear rack and provided with actuating means.
- 40 33. A conveyer mechanism for moving sheet metal barrel drums to beading means for producing circumferential beads on opposite ends of each of said drums, said conveyer mechanism including a track over which said drums are conveyed to said beading means and which has rails adjustable laterally relatively to the path of the drums to suit drums of different length, drum propelling means including a plurality of longitudinal feeding bars which are 45 adjustable laterally relative to the path of the drums, yielding dogs mounted on said bars and adapted to engage with the front and rear side of each drum, guide rollers for said feeding bars, a laterally adjustable bracket carrying said rollers, a gear rack connected with said bracket, and a gear pinion meshing with said gear rack and provided with actuating means.
- 45 34. A conveyer mechanism for moving sheet metal barrel drums to beading means for producing circumferential beads on opposite ends of each of said drums, said conveyer mechanism including a track over which said drums are conveyed to said beading means, and a propelling mechanism for moving said drums over said track including a feeding frame having a plurality of longitudinal feeding bars, a plurality of transverse bars, brackets secured to said longitudinal bars and adjustable on the transverse bars, feed dogs mounted on said longitudinal bars, longitudinal gear racks connected with said feeding frame, gear wheels meshing with said racks, and an oscillating shaft upon which said gear wheels are adjustable in a direction lengthwise of said shaft.
